B. T. STEBER

LOOM

Filed Dec. 16, 1924

BERNARD T. STEBER,

By *Edgar M. Kitchin*
his attorney.

UNITED STATES PATENT OFFICE.

BERNARD T. STEBER, OF UTICA, NEW YORK.

LOOM.

Application filed December 16, 1924. Serial No. 756,219.

To all whom it may concern:

Be it known that I, BERNARD T. STEBER, a citizen of the United States, residing at Utica, in the county of Oneida and State of New York have invented certain new and useful Improvements in Looms; and I do hereby declare the following to be a full, clear, and exact description of the invention, such as will enable others skilled in the art to which it appertains to make and use the same.

This invention relates to improvements in hand looms, and more particularly to take-up mechanism thereof for the finished fabric.

Among the objects in view are the avoidance of waste of warp yarn, the automatic taking up of the finished fabric, and the provision for the maximum length of finished fabric.

A further object in view is the constant exercise of a gravity pull on the finished fabric and the warp shed for insuring uniformity in the character of the fabric.

With these and further objects in view as will in part hereinafter become apparent and in part be stated, the invention comprises certain novel constructions, combinations and arrangements of parts as subsequently specified and claimed.

In the accompanying drawings,—

The figure is a view partly in elevation and partly in section of loom apparatus embodying the features of the present invention.

Referring to the drawings by numerals, 1 indicates the frame of a hand loom having the usual heddles 2, 2, for maintaining and operating the shed 3, and having a warp beam 4. A reed 5 and its actuating lever 6 are shown, and preferably embody the details of construction of an invention presented in an application for United States Letters Patent filed on the same date with this application. The lever 6, as set forth in greater detail in said co-pending application, consists of a pair of arms pivoted at the rear of the machine and connected by a hand bar at the front, the reed 5 having a frame with end plates overlapping the arms of the lever 6 and pivoted thereto at 7 for allowing the reed 5 to come to rest on a part of the frame 1 before the lever 6 reaches its lowermost position, whereby the reed 5 is

adapted to provide a track over which the shuttle is designed to be passed as it is thrust through the shed 3.

The warp beam 4 may be of any type desired, so far as the present invention is concerned, and is preferably provided with a stop 8, or with friction means, not illustrated, so as to control the let-off of warp. The stop 8, as illustrated, consists merely of a pawl adapted to be dropped into the path of rotation of a part of the beam 4 for holding the same against release of warp, the pawl 8 being also designed to be swung upon its pivot for releasing a section of warp as required.

The warp extending from the beam 4 is passed about an idler roller 9 journaled in the lower portion of the frame 1, and the warp extends thence upward through the heddles 2, 2, through which it is laced in the usual manner to form the shed 3, and on up through the reed 5 to and about a guide roller 10 journaled in the upper portion of the frame.

An operating frame is arranged outside of the frame 1, and consists of a pair of arms 11 connected by an appropriate cross piece 12, the lower ends of the arms 11 being journaled on the extended ends of the roller 9 outside of the frame 1, or otherwise appropriately journaled, preferably approximately co-axially with the roller 9. The arms 11 extend upwardly substantially to the top of the frame 1, and are connected at their upper ends by a fabric take-up roller 13 journaled in said arms 11 and adapted to be retained in any given position by a pawl 14 engaging a ratchet 15 formed on or appropriately fixed to the roller 13. An operating handle 16 is adapted to enable the pawl 14 to be readily manually released from its engagement with ratchet 15 to allow the roller 13 to be rotated, as when removing a complete roll of fabric. The handle or lever 16 is so located as to form a counterbalance for normally retaining the pawl 14 in engagement with ratchet 15. An operating crank 17 is fixed to and outstands from one of the ends of the roller 13 for taking up finished fabric during weaving.

When the warp is first applied, it is laced through the parts as described above and passed over the guide roller 10 and connected with the usual pins or other appropriate

anchorage devices on the take-up roller 13, care being exercised to see that the arms 11 are in their most nearly upright position: that is, in the position for having the roller 13 as close to the guide roller 10 as possible for avoiding waste of warp.

The weaving operation is conducted largely after the manner of an ordinary hand loom, the shuttle being thrust through the 10 shed along the reed 5, the reed lifted and caused to strike the weft into place by the upward swinging of the lever 6, and then the heddles 2 reversed and the operation repeated. This is continued until a quantity 15 of fabric extends downward from the guide roller 10 of a length best determined by the operator to suit himself, say, for example, six inches. When this has been done, the operator lifts the pawl 8 and releases a proportional quantity, say six inches, of warp. 20 As this releasing operation is occurring, the roller 13 will be moving by gravity away from the roller 10 so as to take up the finished fabric and leave the apex of the shed 25 where it was at the starting of the operation. The weaving continues and the release of additional fabric occurs from time to time until the take-up roller 13 reaches the limit of its downward movement, as by conflict of 30 some part of the pivoted frame which carries the roller 13 with some part of the frame 1. When the descent of roller 13 has reached its limit, the operator merely winds up the roller 13, the pawl 14 clicking past the 35 ratchet teeth and locking the roller 13 in the position in which the operator happens to leave it. As the roller 13 is rotated and the fabric wound thereon, the upper ends of the arms 11 will be proportionally elevated 40 and brought back toward or to the initial position as seen in the drawings; whereupon the parts are ready for a continuation of the operation.

It will be observed that the take-up roller 13 with its pivotally mounted carrying arms or frame will function effectively with warp beams of various descriptions, and that the one shown with its detent or locking pawl 8 is employed merely for purposes of illustration. A warp beam having a frictional let-off, such as some times employed in power looms, could very well be utilized, and in that event the operator would continue to weave without interruption until the roller 13 reached the limit of its downward movement, when the operator would have to stop weaving long enough to wind up the finished fabric on the roller 13 sufficiently to allow continued operation. Of course, care would 50 have to be exercised with the friction release to see that the friction was set to compensate for the increasing pull of the roller 13 and its connected parts and the fabric rolled thereon. Or any appropriate compensating counterbalance, such as a weight or a spring, 55

coiled or otherwise, may be utilized to resist the descent of the upper ends of the arms 11 proportionally to the increase in the downward stress of the upper portions of arms 11 as they approach the horizontal, so as to 70 cause the gravity descent of such upper portions to exert substantially a uniform pull on the fabric being woven.

The beater 6, reed 7 and co-operating parts are not specifically claimed herein since they 75 are made the subject matter of my co-pending application Serial No. 756,218, filed December 16, 1924.

What is claimed is:—

1. In loom mechanism, the combination, 80 with weaving means, of a take-up roller therefor, and a swinging support for the roller adapted to swing for affording a constant stress in a direction for causing the taking up of finished fabric. 85

2. In loom mechanism, the combination, 90 with weaving means, and a guide therefor for guiding finished fabric, of a take-up roller adjacent the guide, and a pivoted support for the take-up roller adapted to swing on its pivot for affording a constant stress tending to move the take-up roller in a direction away from the guide. 95

3. In loom mechanism, the combination, 95 with weaving means, and a guide for the finished fabric, of a take-up roller adjacent the guide, and means for stressing the take-up roller away from the guide for tensioning the finished fabric.

4. In loom mechanism, the combination, 100 with weaving means, and a guide for finished fabric, of an arm pivotally mounted and having its free end portion extending adjacent said guide, and a take-up roller journaled in said free portion of the arm in 105 position for being stressed by gravity away from the guide for tensioning the finished fabric.

5. In loom mechanism, the combination, 110 with weaving means, and a guide for the finished fabric thereof, of a pivotally mounted frame extending in an inclined plane to a point adjacent the guide, and a take-up roller carried by said frame, the frame being left free to swing by gravity 115 for tensioning the finished fabric.

6. In loom mechanism, the combination, 120 with weaving means, and a guide for the finished fabric, of a pivotally mounted frame extending to a point adjacent said guide, and a take-up roller carried by said frame, the frame being arranged to have that portion carrying the roller gravity-stressed tending to move the frame on its pivot for moving the roller away from the 125 guide for tensioning the finished fabric.

7. In loom mechanism, the combination, 130 with a loom frame, weaving means carried thereby, and a guide for the finished fabric, of a swinging frame having arms adja-

cent the sides of the loom frame and pivoted at their lower ends to the loom frame to swing freely by gravity, said side arms extending upwardly on an inclined plane 5 to a point adjacent the guide, and a take-up roller carried by the upper portions of said arms adjacent said guide, and adapted to receive and tension finished fabric incident to the gravity movement of the swing-
10 ing frame.

8. The combination with a loom frame, weaving mechanism carried thereby, a guide at the upper portion of the frame, a warp guiding idler at the lower portion 15 of the frame, arms pivoted co-axially with said idler and extending on an inclined plane to a point adjacent the guide, said arms being free to swing by gravity, and a take-up roller rotatably carried by said 20 arms adjacent said guide for receiving the finished fabric and tensioning the same in-

cident to gravity swinging of the pivoted arms.

9. In loom mechanism, the combination, with a loom frame, and warp shed maintaining and shifting means, of a pivotally mounted support, and a fabric carrier sustained by the support at a point spaced from the pivot thereof, the support being located relative to the axis of its pivot for 25 moving about the pivot by gravity, the fabric carrier being adapted to receive the finished fabric from the shed and to exert a yielding tension on the shed incident to the tendency of the carrier support to swing 30 about its pivot.

In testimony whereof I affix my signature in presence of two witnesses.

BERNARD T. STEBER.
